INFANT'S SHOE

George E. Kettner, Mamaroneck, N. Y.

Application February 20, 1953, Serial No. 23,709

Term of patent 14 years

(Cl. D7—7)

To all whom it may concern:

Be it known that I, George E. Kettner, a citizen of the United States, residing at 325 Union Avenue, county of Westchester, State of New York, have invented a new, original, and ornamental Design for an Infant's Shoe, of which the following is a specification, reference being had to the accompanying drawing, forming part hereof.

The figure represents a perspective of an infant's shoe, embodying my new design. The opposite side of the shoe is substantially the same in appearance as the side shown.

What I claim is:

The ornamental design for an infant's shoe, substantially as shown and described.

GEORGE E. KETTNER.
